UNITED STATES PATENT OFFICE.

EDWIN PRESTAGE, OF STOKE NEWINGTON, LONDON, ENGLAND.

HIGH-PRESSURE GAS-COMPRESSOR.

1,167,658.

Specification of Letters Patent. Patented Jan. 11, 1916.

Application filed October 23, 1914. Serial No. 868,310.

To all whom it may concern:

Be it known that I, EDWIN PRESTAGE, a subject of the King of Great Britain, residing at 74 Rectory road, Stoke Newington, in the county of London, England, have invented new and useful Improvements in and Relating to High-Pressure Gas-Compressors, of which the following is a specification.

My invention relates to improvements in high pressure gas compressors, designed more particularly for compressing ammonia or carbonic acid gas for refrigerators.

Those high pressure compressors now in use for the purpose of compressing ammonia or carbonic acid gas rarely work at a pressure below a hundred pounds per square inch, such compressors have been fitted with mushroom valves, with the result that only compressors with a slow piston speed can be used satisfactorily owing to the valve slip occasioned with the higher piston speeds.

My invention is designed to provide means whereby such high pressure compressors can be economically worked with safety at a high piston speed.

My invention comprises the use in a high pressure compressor of a sleeve valve arranged between the piston and the cylinder and reciprocated in a partly contrary direction to the direction of the piston.

According to my invention a series of gas inlets or ports are spaced around the wall of the cylinder or liner, and a series of ports in the sleeve valve are adapted to register in one position of said valve with said gas inlets, while the gas outlets are arranged above said gas inlets in the cylinder head. The said gas outlets comprise a series of channels cored out on the inner surface of the sleeve valve and forming the outlet ports from the cylinder leading to a gas chamber of large area. These outlet ports are combined with packing rings adapted to prevent the gas from leaking over the top of the sleeve valve or back into the cylinder and thus relieving the top and outer surface of said sleeve from head pressure, while owing to such channel outlet ports being arranged parallel with the

axis of the sleeve there is no sudden change of direction of flow of the compressed gas passing through said outlets from the cylinder, thus preventing a waste of energy through the heating of the gas during its passage therethrough.

My invention is illustrated by way of example in the accompanying drawings, in which—

Figure 1 is a sectional elevation partly broken away of the gas compressor of my invention, and Fig. 2 is a plan view on the line A—B of Fig. 1.

Referring now to the drawings, I arrange in the wall of the cylinder or liner 13 an annular chamber 16 connected with the gas suction pipe. Suitably spaced around the cylinder or liner 13 a series of gas inlets 17 are arranged, said inlets connecting the annular chamber 16 with the cylinder. The sleeve valve 5 is provided with corresponding series of ports 18 adapted to register in one position of the sleeve valve with said gas inlets 17.

1 indicates the gas discharge outlet; 2 indicates a gas chamber of large area above the false head 3 of the cylinder which is retained in position by the spring 4 which rests upon the guide webs 11. The sleeve valve 5 has a series of channels 6 cored out on the inner surface of said sleeve. These channels form outlet ports from the cylinder and lead to passages 7 opening into the said chamber 2, but closed by the valve formed by the ring 8 shown more particularly in Fig. 2, the said ring being pressed down against the orifice of the said passages 7 by means of springs 9 and pins 10 mounted in slots cut in the said guide webs 11 projecting from the spindle of said cylinder false head 3.

It will be obvious that when compressed gas is admitted to the passages 7 through the channels 6 of the sleeve valve 5 the pressure of the gas will lift said ring 8 against the pressure of the springs 9 and thus allow the passage of the gas into the chamber 2 which is of comparatively large area, with-

out any sudden change of direction of flow during the passage of the gas from the cylinder.

12 indicates an annular lead washer for holding the liner 13 in place and preventing it from rocking during the reciprocation of the sleeve valve 2.

14 indicates a packing ring for preventing the gas from leaking over the top of the sleeve valve and 15 indicates a packing ring for preventing the gas from leaking back into the cylinder.

The false head 3 fits loosely in the cylinder and projects into the sleeve valve, while 15 the outlet ports or channels 6 cored out on the inner surface of said sleeve valve are adapted to register with the cut off edge of the false head.

The sleeve valve 5 is conveniently provided at its lower end (not shown) with an extending lug on which is mounted a spindle on which is pivotally mounted a head carrying a strap encircling an eccentric carried by a web of the engine crank shaft. It 25 must be understood however, that the exact method of reciprocating the sleeve valve 5 may be varied and forms no part of the present invention.

What I claim is:—

30 1. A high pressure compressor for ammonia or carbonic acid gas comprising a cylinder with a series of gas inlets spaced around its wall, a piston reciprocating in said cylinder, a sleeve valve reciprocating between the 35 piston and the cylinder with a series of ports adapted to register with said gas inlets in one position of said valve and with gas outlet passages on the inner surface of said sleeve valve adapted to register with the cut-off edge of a cylinder head projecting into said sleeve valve.

2. A high pressure compressor for ammonia or carbonic acid gas comprising a cylinder with a series of gas inlets spaced around its 45 wall, a piston reciprocating in said cylinder, a sleeve valve reciprocating between the piston and the cylinder with a series of ports adapted to register with said gas inlets in one position of said valve, a series of channels cored out on the inner surface of the upper end of said sleeve valve adapted to form gas outlet passages from said cylinder, a false head in the top of said cylinder projecting into said sleeve valve and provided 55 with ports registering with the channels in said sleeve valve and leading to a gas chamber above said false head.

3. A high pressure compressor for ammonia or carbonic acid gas comprising a cylinder 60 with a series of gas inlets spaced around its wall, a piston reciprocating in said cylinder, a sleeve valve reciprocating between the piston and the cylinder with a series of ports

adapted to register with said gas inlets in one position of said valve, a series of channels cored out on the inner surface of the upper end of said sleeve valve adapted to form outlet passages from said cylinder, a false head in the top of the said cylinder projecting into said sleeve valve with ports 70 registering with the channels in said sleeve valve and leading to a gas chamber above said false head and packing rings adapted to prevent the gas from leaking over the top of said sleeve valve back into said cylinder. 75

4. A high pressure compressor for ammonia or carbonic acid gas comprising a cylinder with a series of gas inlets spaced around its wall, a piston reciprocating in said cylinder, a sleeve valve reciprocating between the piston and the cylinder with a series of ports adapted to register with said gas inlets in one position of said valve, a series of channels cored out on the inner surface of the upper end of said sleeve valve parallel with 85 the axis of said sleeve valve and adapted to form outlet passages from said cylinder, a false head in the top of said cylinder projecting into said sleeve valve with ports registering with the channels in said sleeve valve and leading to a gas chamber above 90 said false head, and packing rings adapted to prevent the gas from leaking over the top of said sleeve valve back into said cylinder.

5. A high pressure compressor for ammonia or carbonic acid gas comprising a cylinder with a series of gas inlets spaced around its wall, a piston reciprocating in said cylinder, a sleeve valve reciprocating between the piston and the cylinder with a series of ports 100 adapted to register with said gas inlets in one position of said valve, a series of channels cored out on the inner surface of the upper end of said sleeve valve adapted to form outlet passages from said cylinder, a false head in the top of the cylinder projecting into said sleeve valve with ports registering with the channels in said sleeve valve and leading to a gas chamber above 105 said false head and a spring controlled ring 110 closing the orifices of the ports opening into the gas chamber through said false head.

6. A high pressure compressor for ammonia or carbonic acid gas comprising a cylinder with a series of gas inlets spaced around its wall, a piston reciprocating in said cylinder, a sleeve valve reciprocating between the piston and the cylinder with a series of ports adapted to register with said gas inlets in one position of said valve, a series of channels cored out on the inner surface of the upper end of said sleeve valve parallel with the axis of said sleeve valve and adapted to form outlet passages from said cylinder, a false head in the top of said cylinder projecting into said sleeve valve with ports 120

registering with the channels in said sleeve, valve and leading to a gas chamber above said false head, a spring controlled ring closing the orifices of the ports opening into the gas chamber through said false head and packing rings adapted to prevent the gas from leaking over the top of said sleeve valve back into said cylinder.

In testimony whereof I have signed my name to this specification in the presence of 10 two subscribing witnesses.

EDWIN PRESTAGE.
